CLAIM

The ornamental design for sunglasses, as shown and described.

DESCRIPTION

FIG. 1 is a front perspective view of sunglasses showing a front embodiment of my new design;

FIG. 2 is a right side elevation view thereof; the left side elevation view is the mirror image of the right side elevation;

FIG. 3 is a top plan view thereof;

FIG. 4 is a front elevation view thereof;

FIG. 5 is a rear elevation view thereof;

FIG. 6 is a bottom plan view thereof;

FIG. 7 is a front top left perspective view of a second modified embodiment of the design shown in FIGS. 1-6, the front top right perspective view is a mirror image of FIG. 7; FIG. 7 differs from FIG. 1 by the inclusion of a brow bar;

FIG. 8 is a rear elevation view of FIG. 7;

FIG. 9 is a bottom plan view of FIG. 7; and

FIG. 10 is a bottom plan view of the brow bar of FIG. 7 shown separately for clarity of illustration.

FIG. 1

FIG. 2

FIG. 3

FIG. 4

FIG. 5**FIG. 6**FIG. 7

FIG. 8

FIG. 9

FIG. 10
